UNITED STATES PATENT OFFICE.

HENRY FALLER, OF MIDDLE VILLAGE, ASSIGNOR TO JOHN TIMMES, OF BROOKLYN, NEW YORK.

DESIGN FOR A GATE.

SPECIFICATION forming part of Design No. 12,287, dated May 31, 1881.

Application filed April 23, 1881. Term of patent 7 years.

To all whom it may concern:

Be it known that I, HENRY FALLER, a citizen of the United States, residing at Middle Village, in the county of Queens and State of New York, have invented and produced a new and original Design for Gates, of which the following is a specification, reference being had to the accompanying photographic view, forming part thereof.

10 The accompanying photographic illustration represents a front view.

This design comprises the arched top pieces, A, the bottom piece B, straight at the ends and arched in the center, and the side bars, C C, connecting the top and bottom pieces. 15 The top piece, A, is surmounted with convolute stems D and buds E, partly covering bunches of fruit, and a central leaf, F. From the bottom piece, B, depends a central leaf, G, and convolute stems H. The side bars, C C, are ornamented, respectively, with a scroll, I, and a capital, J. In the center of the gate is located 20 a square shield, K, resting upon one of a series of stems, L, emanating from the center of

the bottom piece, B. These stems L support 25 also two approximately circular shields, N N, and have interspersed therewith buds O, two of which inclose bunches of fruit.

What I claim as new, and desire to secure by Letters Patent, is—

30 1. The design for a gate, consisting of the arched top piece, A, the partly-straight and partly-arched bottom piece, B, and the side bars, C C, the whole arranged and ornamented as set forth.

2. The design for a gate, consisting of the arched top piece, A, the partly-straight and partly-arched bottom piece, B, the side bars, C C, the central shield, K, the shields N N, and stems L, the whole arranged and ornamented as set forth.

35 In testimony whereof I have hereunto set my hand and seal in the presence of two subscribing witnesses.

HENRY FALLER. [L. S.]
